ATTORNEY

UNITED STATES PATENT OFFICE.

LUTHER M. MOORE, OF WALLA WALLA, WASHINGTON.

TUG HOOK.

Application filed January 21, 1928. Serial No. 248,305.

This invention relates to tug hooks and has as one of its objects to provide a hook that is adapted to form an ideal securing means, and which while primarily being intended as a tug hook and forming a part of the tug of harness, may, by changes in its body portion to fit conditions, be adapted to other uses of a hook nature.

Another object of the invention is to provide a tug hook adapted to form part of the tug of harness and that will provide an ideal securing means.

A further object of the invention is to provide a tug hook that will protect the tug from being broken by preventing other parts becoming entangled in the hook.

A further object of the invention is to provide a tug hook that will automatically lock itself on the connecting link of the butt chain.

20 A further object of the invention is to provide a tug hook that may be constructed wholly devoid of springs if desired.

A further object of the invention is to provide a tug hook that is simple to construct, efficient for the purpose intended, having ample strength, and that may be available on the market at a reasonable price.

With these and other objects in view, reference is now had to the accompanying drawings in which

Fig. 1 is a side elevation of a fragment of my preferred form of hook;

Fig. 2 is a plan view thereof; and

Fig. 3 is a side elevation of a modified form of tug hook.

Having reference to the drawings, like numerals refer to like parts throughout the several views and the numeral 1 refers to the tug hook in its entirety and consists of a relatively thin fin-like body 2 adapted to be secured in between the straps of a tug by rivets passed through the holes 3, in the usual manner of such construction.

This construction is not shown as it is deemed unnecessary in view of the well known state of the art, and has no bearing on the invention.

The body gradually thickens toward the hook end 4, as shown in Fig. 2, to provide the necessary strength to the hook portion.

On the upper side of the body, and formed integral therewith, is a finger 5 extending in the direction of the hook end, and the finger is positioned and arranged to form with the body a slot or throat, which will be termed the receiving recess 6 as it is auxiliary

to the main channel 7 of the hook, and the finger is completed with a crown 8 formed in its free end for a purpose to be explained.

The hook end, as its name implies, is shaped in hook form and in my preferred form consists of a compound hook 9 comprising an extension piece 10 formed integral with the body 2, with its free end bent upward and back to form a fixed open hook 11, with the point of the hook tapered, as at 12, to project in the direction of the body, to form a throat 13 that merges into the main channel 7 and that is positioned on the center line of the tug hook.

Hingedly attached to the extension, at the hinge point 14, is a keeper hook 15.

The keeper hook normally lays adjacent to the open hook 11, with its throat 16 coinciding with the throat 13 of the open hook, and is provided with a relatively light weight tongue 17, the end 18 of which normally seats in the crown 8, and its hook proper 19 is relatively heavy for the purpose of utilizing gravity to maintain the keeper hook in the normal (closed) position.

The tongue 17 of the keeper hook is of a shape that when the hook is open to receive a link (represented by the dotted circle 20 and the cross hatched circle 21) it is adapted to form part of the receiving recess 6 and provide a mouth thereto opening to the outside of the tug hook.

By referring to the dotted lines in Fig. 1 it will be noted that the link 20 is free to enter the auxiliary throat, and when this condition exists that gravity will cause the tongue to automatically assume the position shown by the solid lines in this Fig. 1 which latter position of the keeper hook opens the throat 13 to permit the link to pass to the initial position shown as at 21.

It will be further noted that with the link 21 in the throats 13 and 16, of both the open hook 11 and the keeper hook 15, that the tongue 17 will be maintained in the closed position, with its end 18 seating in the crown 8, nor can the hook be opened until the link has been partly withdrawn to the receiving recess as a shearing action takes place that would necessitate cutting the link before the tug hook could be opened.

It is therefore obvious that the hook is locked under load, i. e., that the greater the pull, added to the resistance to shearing, the greater would be the power required to open the hook. It is therefore claimed that the

hook is closed securely proportionately with the load.

In my modified form, shown in Fig. 3, a single hook 22 is employed and this hook is likewise hinged to the body and has its throat 23 on the center line, and hence its security is proportionate with the load, as the load will maintain the end 18 in the crown 8.

The tug hook is provided with an eye 24 formed in the edge of the material of which the tug hook is composed, and is constructed to provide a relatively small diametered part 25 to conveniently receive a harness snap (not shown), the purpose being to provide a 15 ring in such a manner that it will not materially weaken the tug hook.

In use, the tug hook is made a part of the harness tug and with the horses in place before the vehicle to be moved, the butt chains 20 thereof are attached as above explained.

Now, at times, one animal will pull ahead of its companion and, being urged ahead, the companion will lunge forward jerking the first animal back. Under these conditions 25 flapping butt chains, side by side, will catch in any projections exposed, quite frequently causing a breakage to the harness, and hence by the use of the above designed hook the butt chain cannot catch as there are no projections capable of engaging the butt chain 30 link.

The eye provides a simple means whereby to lead several animals in a string, and also provides a strong definite place to attach

a halter chain to rather than promiscuously 35 about the harness, at some place not having the strength to resist the sudden pull-back of the led animals.

Obviously, by changing the form of the fin-like body to a link or like form, the hook 40 will readily adapt itself to other uses.

Having thus described my invention, I claim:

In a tug hook, the combination with a body, a finger formed on said body and arranged 45 to provide therewith a receiving recess, adapted for the initial reception of a link, a compound hook comprising an extension formed integral with said body and terminating in an open hook having an elongated 50 throat and adapted as one jaw of a shear, a gravity operated keeper hook hingedly attached to said extension and having a throat coinciding with the throat of said open hook and adapted as the other jaw of the shear, 55 and a stem formed integral with said keeper hook and adapted to separate the receiving recess from the throat when in the open position and to provide communication between the receiving recess and the throat to provide 60 for entrance to the shear by said link for final and complete reception of said link when in the closed position, said link being adapted to prevent movement of said shear until partly withdrawn.

65 In testimony whereof I affix my signature.

LUTHER M. MOORE.
